ATTORNEY

UNITED STATES PATENT OFFICE.

ALBERT BALL, OF CLAREMONT, NEW HAMPSHIRE.

DIAMOND-DRILL-CORE CATCH OR RETAINER.

SPECIFICATION forming part of Letters Patent No. 314,777, dated March 31, 1885.

Application filed November 17, 1884. (No model.)

To all whom it may concern:

Be it known that I, ALBERT BALL, of Claremont, in the county of Sullivan and State of New Hampshire, have invented a new and useful Improvement in Diamond-Drill-Core Catches or Retainers; and I do hereby declare that the following is a full and exact description of the same, reference being had to the accompanying drawings, and to the letters of reference marked thereon.

My invention relates to an improvement in core-receivers for use with diamond and other rotary drills for boring rock, &c.; and my object is to produce a device which will not only receive the core during the progress of drilling, but will as readily retain the same without clogging up the drilling-tube, and while it is intended to be made thin, light, and flexible, it shall at the same time be strong and durable and cheap to manufacture.

The novelty of my invention therein consists of a cylinder with catches and openings, all made out of a blank punched from a single sheet of thin steel, and then converted into a cylinder and tempered, all as more fully hereinafter described, and pointed out in the claims.

For the better comprehension and understanding of this invention, in connection with the description to follow, attention is invited to the accompanying drawings, in which—

Figure 1 shows the blank as punched from a sheet of steel, and the one preferred as the simplest form for making my device. Fig. 2 is a plan of the top end of this blank when converted into a cylinder and otherwise made complete. Fig. 3 is a vertical central section of the same. Fig. 4 is a view in plan of a modified form of the blank. Fig. 5 is a vertical central section of this form when converted into a cylinder and made complete. Fig. 6 is a plan of the upper end of the same, and Fig. 7 is a vertical central section through a drilling-tube and my core-retainer of the modified form.

Like letters of reference indicate corresponding parts throughout the several views.

The blank G (shown in Fig. 1) is punched from a thin sheet of steel, and has on one edge in the direction of its length a series of parallel fingers, F and H, and on the opposite edge, c, which is the base proper, it has a series of open spaces, a a a, which, when the device is

completed and placed in position within the drilling-tube, give free passage to the water, gravel, grindings, and dirt down through and 55 between the core receiver and retainer and the annular drill-head.

After the blank has been punched into the form above described, it is then converted into a cylinder by bringing its two ends together. 60 After this has been done, the fingers F are then bent inward to form spring-catches, and the whole is then tempered to a sufficient and reasonable degree of hardness. The catches F, however, should have sufficient elasticity 65 and spring to yield to the pressure of the core when entering the cylinder G, and to hold and prevent it from dropping back when the drill ceases operation. The body of the device is preferably made short, so as to lessen 70 the liability of being caught by the grit, and its diameter should be sufficient to allow the core to enter it without obstruction.

In the modification, Fig. 4, which does not differ materially from Fig. 1, the blank G has 75 its fingers formed by punching out its central portion, as shown, leaving both longitudinal edges solid, as shown at H, with the exception of open spaces a a a on the bottom, and, if desired, this form may also have similar spaces, 80 x x x, on the upper edge, as shown by dotted lines in this figure. This modified form is completed in the same manner as described with reference to the form shown in Fig. 1, and is similar in all other respects except as 85 regards the fingers F.

In Fig. 7 is shown a section of tubing or a coupling, A, with an annular drill-head, B, screwed into its lower end, and a section of tubing or pipe, C, screwed into its upper end, 90 establishing shoulders d and e, respectively. Between these shoulders is held a core receiver and retainer, G, of the form illustrated in Fig. 5, the base c resting upon the lower shoulder, d, and the fingers or portions H H 95 constituting guides, and bearing against the length of tubing or pipe next above the tube or coupling A.

It will be manifest that my device could be lengthened, if desired, so as to have two or 100 more of the spring-catches in line one above the other, and that it can be attached to and form a part of a long inner core-barrel made in a similar or other manner. In fact, this

device is capable of many modifications without the exercise of invention.

Among the advantages that may be asserted in its favor are that, being made in a single piece, it can be thin and light, thereby leaving ample space between its outside circumference and the inner walls of the drilling-tube for the free passage of water, &c., and dispensing with grooves and other means for this purpose. Moreover, strength and durability are features of this device, and there are no rivets or small removable parts, which make it of special value in connection with the use of diamond-drills, inasmuch as a piece of metal in the hole frequently destroys many carbons and causes much damage.

What I claim, and desire to secure by Letters Patent, is—

1. In combination with an annular diamond-drill head, a cylindrical steel core re-

ceiver, and retainer, with upwardly-extending spring-catches and a series of base-openings, substantially as described.

2. As a new article of manufacture, a cylindrical core receiver and retainer composed wholly of a blank with upwardly-extending catches and a series of base-openings, all punched from a single sheet of steel rolled and tempered, substantially as described.

3. The cylindrical core receiver and retainer G, having upwardly-extending spring-catches F, intermediate its top and base, and a series of openings for the passage of the water, &c., substantially as described.

In testimony whereof I affix my signature in presence of two witnesses.

ALBERT BALL.
